UNITED STATES PATENT OFFICE.

RICHARD T. BARTON, OF NEW HAVEN, CONNECTICUT, ASSIGNOR TO THE
R. T. BARTON COMPANY, OF SAME PLACE.

DESIGN FOR A LAMP-BURNER.

SPECIFICATION forming part of Design No. 22,395, dated May 2, 1893.

Application filed March 10, 1893. Serial No. 465,432. Term of patent 14 years.

To all whom it may concern:

Be it known that I, RICHARD T. BARTON, of New Haven, in the county of New Haven and State of Connecticut, have invented a new 5 Design for Lamp-Burners; and I do hereby declare the following, when taken in connection with accompanying drawing and the letters of reference marked thereon, to be a full, clear, and exact description of the same, which 10 said drawing constitutes part of this specification, and represents a perspective view.

This invention relates to a design for a lamp-burner, and consists in the configuration as shown in the accompanying illustration.

15 The base A, of the burner consists of a wide convex band, merging at its smaller upper end into a very narrow vertical band or fillet B. Directly above this fillet there is a convex band C, the larger upper edge of which 20 merges into the skirt D, of the burner, the lower edge of the said skirt being made im-

perforate, and rounding or convex, and its upper and main portion being perforated and slightly flaring, growing larger as it approaches its upper edge. The gallery or chimney-holder E, of the lamp is located at the upper edge of this skirt, and receives the cone, which rises above the arms E' of the gallery, the said cone being virtually of frustum-of-cone form, although it is very slightly bulging, and has its upper edge turned inward. 25 30

I claim—

The design for a lamp-burner as herein shown and described.

In testimony whereof I have signed this 35 specification in the presence of two subscribing witnesses.

RICHARD T. BARTON.
